UNITED STATES PATENT OFFICE.

CHARLES SEYBOLD, OF DAYTON, OHIO.

CLAMP-CO尤LING DEVICE FOR AUTOMATIC PAPER-CUTTERS.

SPECIFICATION forming part of Letters Patent No. 731,232, dated June 16, 1903.

Application filed October 28, 1901. Serial No. 80,296. (No model.)

To all whom it may concern:

Be it known that I, CHARLES SEYBOLD, a citizen of the United States, residing at Dayton, in the county of Montgomery and State of Ohio, have invented certain new and useful Improvements in Clamp-Coupling Devices for Automatic Paper-Cutters, of which the following is a full, clear, and exact description, reference being had to the accompanying drawings, forming part of this specification.

My improvements relate to that class of automatic paper-cutters in which the driving mechanisms for the clamp and for the knife have been connected by a friction-clutch to hold rigid the paper, but to allow the knife to continue its operation, the clamp stopping on the paper and the friction-clutch allowing the mechanism to slip.

For large paper-cutting machines with paper that is at all spongy almost crushing strength in the clamp is needed to hold the paper, and in machines of this class it has been customary to connect the clamp with the knife cutting mechanism, so that the operation of the knife shall drive the clamp. The problem presented, therefore, with large machines was to shorten up the leverage between the clamp and knife-driving mechanism in order to obtain the maximum amount of clamp-power; but the difficulty has been that in shortening the leverage between the clamp-pulling bars and the clamp-driving shaft there has not been sufficient stroke or movement of the knife-carrying mechanism to obtain the requisite movement of the clamp. In addition to this it has been customary to drive the clamp-shaft through the medium of the knife-carrying frame, and consequently the gearing or other mechanism employed in the machine for driving the knife has also had to sustain the operations of the clamp.

It is the purpose therefore of my invention to devise a construction in which the knife-driving mechanism shall be relieved from this strain of driving the clamp and in which ample stroke for the clamp can be obtained to furnish the requisite clamp movement notwithstanding a very short leverage between the clamp-pulling bars and the clamp-shaft. In the drawings, Figure 1 is a side elevation of the paper-cutting machine with my improved means for driving the clamp. Fig. 2

is a rear elevation of one side of the paper-cutting machine, showing my improvements. Fig. 3 is a detail front elevation of my friction-clutch.

In illustrating the novel features of my present invention I have only shown one side of the machine, sufficient to make clear my present invention, which merely relates to the method of driving the clamp in machines of the class under consideration.

My improvements are illustrated and applied to that class of paper-cutting machines which is fully shown and described in my prior patent, No. 511,972, of January 2, 1894, and I have not considered it necessary to illustrate or describe the details of such a paper-cutting machine other than to say that A is one of the end standards of the machine; B, the knife-carrier frame; C, the clamp, and D the table. The knife-carrier and its knife are driven in any well-known way, preferably by driving-shaft E and gearing, such as shown in my aforesaid patent. The clamp C is connected with its driving mechanism by pulling-bars F, one on each side.

G is the clamp-shaft, carrying the segment-gear H, which meshes with a rack L on the lower end of the pulling-bars, so that the rotation or oscillation of the clamp-driving shaft G will, through the medium of the segment gear and rack, actuate the pulling-bars F to raise and lower the clamp C, as required.

Mounted on the clamp-shaft G is a friction-clutch, such as is shown in my heretofore-mentioned patent, which, in brief, consists of the split ring a, keyed to the shaft G and provided with a block b, mounted on one of the spokes of the band between the ends thereof. This block b is rotated by the lever c, acted on by the screw d, so that by adjusting the screw the split band a may be opened out. Mounted around this split band a is a ring e, which has heretofore been coupled to the knife-carrier frame, so that the movement of the knife-carrier frame would, through the medium of the split-band clutch, actuate the clamp-shaft and the clamp-pulling bars to raise and lower the clamp. As has already been stated, however, with this construction, the throw of the knife-carrier being limited, the leverage between the clamp-shaft and the clamp-pulling bars has had to be so geared in

order to obtain the necessary movement of the clamp that the requisite power needed in large machines with spongy paper could not be obtained for the clamp. I have therefore disconnected entirely the clamp-shaft from the knife-driving mechanism. The ring-band *e* in my improved machine is connected by a connecting-bar *M* with the crank-pin *N* on the gear-wheel *O*, which is mounted in a suitable bearing on the side of the frame. This gear *O* meshes with the pinion *P*, whose shaft is journaled in suitable bearings on the frame and carries at its inner end, just within the side standard *A*, the gear *R*, which in turn meshes with a pinion *S*, mounted on the driving-shaft *E* of the machine. The size and number of teeth in the several pinions and gear-wheels connecting the driving-shaft *E* of the machine with the connecting-rod *M* of the friction-clutch are so arranged that a complete stroke for the clamp shall be obtained for each complete throw of the knife and so that the throw of the clamp shall be slightly ahead of the knife movement, as it is of course essential that the clamp should reach and compress the paper before the knife begins its work.

Having thus described my invention, what I claim, and desire to secure by Letters Patent, is—

30

1. In a paper-cutting machine, the combination, with the main driving-shaft of the machine and a clamp-shaft with means for connecting same to the clamp, of a friction-clutch mounted on said clamp-shaft, and 35 train of gears and pinions with connecting-rod coupling said friction-clutch directly to said main driving-shaft, substantially as shown and described.

2. In a paper-cutting machine, the combination, with the main driving-shaft of the machine, a clamp-shaft, and a clamp, with pulling-bars therefor and rack on the pulling-bars with segment-gears on the clamp-shaft, of a friction-clutch, mounted on said clamp-shaft and train of gears and pinions with connecting-rod coupling said friction-clutch directly to said main driving-shaft, substantially as shown and described. 45
